KEY LOCKED FASTENING FOR ATTACHE
CASES AND THE LIKECharles William Cheney, Soho, Birmingham,
EnglandApplication April 25, 1945, Serial No. 590,143
In Great Britain February 25, 1944

4 Claims. (Cl. 70—67)

1

The invention relates to fastenings for attaché cases, and the like, of that kind comprising two principal parts, the one (for example) a hinged hasp-member, to be engaged by a bolt, and the other a bolt-member provided with key-locking mechanism and having upon the front plate of its casing a forwardly projecting knob which can be either a fixture on said casing, or slideable by hand to retract the bolt against its normal spring loading, said bolt if the knob is a fixture on the casing being hand-retracted by a separate member such for example as a slideable stud.

In fastenings of this kind the key-locking mechanism for the bolt-member is usually of a very simple-key character, providing little safety against opening an attaché case or the like, mainly because such fastenings must be very cheaply produced, and in themselves are of simple construction not lending themselves readily to a more robust key-locking mechanism.

The invention refers to the bolt-member only of said fastenings, and provides upon the front plate of the casing a hollow projecting knob containing a combination of parts constituting a key-supporting and key-selecting mechanism for use with a key of a type having a flat shank longitudinally grooved and transversely notched along one edge; such mechanism providing for the use of a much more complex character of key, and for easy combinations in key change. Essentially, the invention arranges for the key-change stops to be disposed within and to form part of the hollow knob; but, further, the invention provides as part of the bolt-member an effective seating for the forward end of the key to engage and turn in, to ensure that the notches of the key shall always correctly register with the fixed key-selectors contained within the knob.

A convenient arrangement of the invention provides within the hollow knob a revolvably mounted key-supporting piece, and fixed key-selector plates adapted to co-operate with a flat key shank longitudinally grooved and transversely notched correctly to the piece and plates.

The knob is of a flat character and, preferably, circular, being open at back and having a circular hole through its front wall, and the key-supporting piece and key-selecting plates are arranged face to face within the hollow interior of said knob so that the piece is revolvably with the key and the selecting plates are fixed, each of the latter having, to form a stop abutment, a central hole through it of a different diameter to the hole through the other plates, and a radial gap extending from said hole; all of which will be

2

hereinafter specifically described in connection with one arrangement of the accompanying drawings.

Further, according to the invention the knob casing, the revolvably key-supporting piece and the key-selector plates are assembled as a knob-unit, connectable to the casing of bolt-member if the knob is fixed to said casing, or connectable to the bolt through openings in the lock casing if the knob is a slideable one withdrawing the bolt; the unit-knob also including a fixed plate lying within the knob adjacent the face of the front plate of the bolt-member and having connecting lugs, or branches, for rivetting the bolt-member to the casing or to the bolt.

The abutments or stops for key selecting may be provided as projections upon a short length of tube fixed axially within the knob, and with which is used a revolvably key-supporting piece, aforesaid.

Other constructional combinations according to the invention will be hereinafter clearly set forth by the description hereinafter appearing with reference to the accompanying drawings illustrating two forms of bolt-member, one form with the knob slideable on the casing to retract the bolt, and the other form with the knob fixed to said casing and a separate hand-member provided to retract the bolt.

One arrangement according to the invention is represented in the drawings by Figs. 1 to 11 in which the knob is slideable on the casing and is connected therethrough to the bolt; while a further arrangement of the invention is represented by Figs. 12 to 14 wherein the knob is fixed to the casing, and the bolt is retracted by a separate hand member applied to the casing and to the bolt.

40 Fig. 1 is a front elevation of the bolt member.

Fig. 2 is a longitudinal section of Fig. 1 on the dotted line A but on a larger scale.

Fig. 3 is a transverse section of Fig. 1 on the dotted line B.

45 Fig. 4 is an elevation with the front plate removed, but indicated by dotted lines.

Fig. 5 is a transverse section of the bolt only (Fig. 3), with the back plate of the casing in dotted lines.

50 Fig. 6 is a side elevation of the key to be used with the bolt-member, and

Figs. 7, 8, 9, 10, and 11 are separate views of the key supporting and key-selecting plates.

Fig. 12 is a front elevation similar to Fig. 1.

Fig. 13 is an elevation similar to Fig. 12 but

with the front-plate and the back-plate of the casing indicated in dotted lines only, and

Fig. 14 is a separate view of the back plate of the casing.

The casing 1 comprises front plate 1a and back plate 1b and contains a slidable bolt 2 and key operated bolt-locking devices 3, all of which are constructed, applied, and arranged to operate in a manner well known in the art; the invention consisting essentially in a key-supporting and key-selecting mechanism contained within the hollow projecting knob applied to the front plate of the casing, with the exception of minor changes in the bolt or casing co-operative with said key-supporting and key-selecting mechanism and the key, the whole of which will be herein-after particularly described.

The hollow knob 4 is closed at its sides, is open at its back and is closed at its front wall except for a circular hole 4a, said front wall being also provided with a gap 4b for key insertion.

Engaging the hole 4a in the front wall of the knob to turn therein is a key-supporting piece 5 having a central boss 5a to fit the hole 4a and through which a key opening 5b passes, said piece 5 having a boundary flange 5c to face up to the inside surface of the front wall of the knob, as clearly represented by Figs. 2 and 3. Surrounding the flange 5c is a ring-like support, 6, fixed within the knob, and within whose bore, 6a, the key-supporting piece 5 is revolvable as well as being revolvable in the hole 4a of the front wall of the knob.

At the back of the ring-like support 6 are three flat key-selecting plates 7, 8, and 9, lying against each other and with the forward one 7 lying against the support 6, while inwardly of the plate 9, and still within the knob, is a further plate 10 lying against the plate 9 and having right-angled lugs 10a and 10b as parts of it to connect it to the bolt 2 as clearly shown in Fig. 3; all these plates, 7, 8, 9, and 10, together with the ring-plate 6, being rivetted together and to the front wall of the knob casing at 11 and 12, so that they become fixed to the knob casing concentric with the key-supporting piece 5, while allowing said key-supporting piece to revolve within the knob casing.

Each of the selector-plates 7, 8, and 9, is formed with a central hole 13 of a different diameter to the hole through the other plates, and has a radial gap 14 extending from said hole for key entrance and to provide at the junctions between the hole and the gap stop-abutments or key-selector projections 15 which operate either to admit of a key turning if correctly grooved and notched, or to prevent a key turning if an incorrect or false key is tried.

The key 16, Fig. 6, is of a type, having a flat shank grooved longitudinally at 16b and notched transversely at 16c, the groove to co-operate with a longitudinal rib 5d within the key-hole of the key-supporting piece 5, and the notches to co-operate with the stop-abutments or selector-projections 15 of the central holes in the selector plates 7, 8, and 9, so that only a key correctly grooved longitudinally and notched transversely can be inserted into the bolt-member and be turned so that its forward bit 16d can operate the locking mechanism 3 for locking and unlocking the bolt 2; and here it will be appreciated that by interchange of the piece 5, and the selector-plates 7, 8, and 9, different key-changes can be provided within the knob.

The invention also provides a circular forward

end 16e on the key 16, and upon the bolt 2 a circular seating 2a for this circular end to enter to a stop-shoulder 16f and turn in to correctly position the notches 16c to the stop-abutments or projections 15 of the selector plates 6, 7, and 8.

In the arrangement of the invention Figs. 12 to 14 the knob 4, containing the key-supporting piece 5 and the plates 6, 7, 8, and 9, is connected by the lugs 10a and 10b to the fixed back plate 1b of the casing instead of to the bolt 2, so that the knob 4 is fixed on the face of the front plate 1a; a separate hand-operated knob 17 being provided on the face of said front-plate and connected with the bolt 2 to hand retract the bolt against its spring, the lugs 10a, 10b passing through clearance slots 18 in the bolt and rivetting in holes 19 in the back plate of the casing, the knob 17 being connected to the bolt 2 by a shank on the back of it being rivetted in a hole 20 provided in the bolt.

As previously stated, except for the key-seating 2a either in the bolt 2 Figs. 1 to 9 or in the back plate of the casing Figs. 12 to 14, said casing, bolt and key-operated bolt-locking device 3 are substantially as ordinarily, any minor change being only consequent upon the knob 4 and the parts contained within it being either slidable on the casing or fixed on said casing.

Instead of the selector plates 6, 7, and 8 providing stop-abutments or key-selector projections such as 15, a tubular split member formed with said abutments or projections can be substituted and fixed within the knob 4 axially to pass the key through at the split and to co-operate with the notches in the key; the revolvable key-supporting piece 5 being provided to operate as described. Such a tubular member can be interchangeable to the knob casing, and therefore can provide for different key-changes.

What I claim is:

1. In key-locked fastenings of the kind described, a bolt-member combining a casing, a bolt in the casing, bolt-locking devices within the casing, a seating in the casing for the forward end of the key to engage, a hollow stationary knob on the face of the casing and which is open at its back and has a circular and notched hole through its front wall; a revolvable key-supporting piece within the knob and hole, fixed key-selecting projections within the knob at the back of the key supporting piece, and means for hand retracting the bolt including an additional member slidable on the face of the casing and connected with the bolt.

2. In key-locked fastenings of the kind described, a bolt-member combining a casing, a bolt in the casing, bolt-locking devices within the casing, a seating in the bolt for the forward end of the key to engage, a hollow knob mounted slidably on the face of the casing and which is open at its back and has a circular and notched hole through its front wall, a revolvable key-supporting piece within the knob and hole, fixed key-selecting projections within the knob at the back of the key-supporting piece, and means connecting said slidable knob with said bolt.

3. In key-locked fastenings of the kind described, a bolt-member combining a casing, a bolt in the casing, bolt-locking devices within the casing, a seating in the bolt for the forward end of the key to engage, a hollow knob mounted slidably on the face of the casing and which is open at its back and has a circular and notched hole through its front wall and within which a

revolvable key-supporting piece and fixed key-selecting projections are provided to constitute a knob-unit, and means connecting said knob with the bolt and which also forms a part of the knob-unit.

4. In key-locked fastenings of the kind described, a bolt-member combining a casing, a bolt in the casing, bolt-locking devices within the casing, a seating in the bolt for the forward end of the key to engage, a hollow knob mounted slidably on the face of the casing and which is open at its back and has a circular and notched hole through its front wall, a revolvable key-supporting piece within the knob, key-selecting projections within the knob at the back of the key-supporting piece and which comprise a series of annular superposed discs of different inner diameters and uniform outer diameter fitting the knob, each disc being provided with a radial notch to permit insertion of the key, said discs being

assembled in the knob as a unit with their notches aligned with one another and with a notch in the front wall of the knob, and means for connecting said knob with the bolt and which also forms a part of the knob-unit.
